[57] **CLAIM**

The ornamental design for a pressed-in pipe plug, as shown and described.

DESCRIPTION

FIG. 1 is a top, front and left side perspective view of a first embodiment of a pressed-in pipe plug showing our new design;

FIG. 2 is a front elevational view of FIG. 1;

FIG. 3 is a left side elevational view of FIG. 1 and a mirror image of a right side thereof;

FIG. 4 is a rear elevational view of FIG. 1;

FIG. 5 is a top plan view of FIG. 1;

FIG. 6 is a bottom view of FIG. 1;

FIG. 7 is a top, front and left side perspective view of an alternative embodiment of a pressed-in pipe plug showing our new design;

FIG. 8 is a front elevational view of FIG. 7;

FIG. 9 is a left side elevational view of FIG. 7 and a mirror image of a right side view thereof;

FIG. 10 is a top plan view of FIG. 7; and,

FIG. 11 is a bottom plan view of FIG. 7.

The broken line showing of the pipe is for illustrative purposes only and forms no part of the claimed design.
